UNITED STATES PATENT OFFICE.

JOHN GOOD, OF BROOKLYN, NEW YORK, ASSIGNOR TO GOOD INVENTIONS CO., OF BROOKLYN, NEW YORK, A CORPORATION OF NEW YORK.

HACKLE-CHAIN APPARATUS.

1,191,959.

Specification of Letters Patent. Patented July 25, 1916.

Application filed June 15, 1915. Serial No. 34,143.

To all whom it may concern:

Be it known that I, JOHN GOOD, a citizen of the United States, and a resident of the borough of Brooklyn, county of Kings, city 5 and State of New York, have invented certain new and useful Improvements in Hackle-Chain Apparatus, of which the following is a full, true, and complete specification.

10 The invention relates to hackle-chain apparatus used in long line combers and allied machinery, and has for its object to improve the construction and operation thereof in a number of particulars.

15 The machine is adapted for working the commercial grades of hemp, jute, and fibers of substantially the same length, being made heavier for longer fibers and lighter and with more pins for shorter fibers.

20 The improvements affect more especially, though not necessarily exclusively, those forms of such apparatus wherein two or more chains driven at different speeds are employed in series, important objects being 25 to make possible a very short nip upon the fiber at proximate ends of the chains, and at the receiving end to secure the benefits of direct penetration heretofore obtained in the relatively slow and less desirable gill-box 30 type of apparatus. These and other advantages of construction and operation are obtained by the improvements which will now be described, comprising particularly certain features of construction, combination 35 and relation in respect to the dogs and trackways for controlling the rake of the gill-pins and the means for guiding the chains through their courses.

In the accompanying drawings: Figure 1 40 is a side elevation, showing proximate portions of two chains; Fig. 2 is a plan view of Fig. 1, the apparatus being broken away centrally and longitudinally for economy of space; Fig. 3 is a vertical cross-section on the line 3—3 of Fig. 1, the apparatus being 45 broken away centrally as in Fig. 2; Fig. 4 is a vertical longitudinal section on the line 4—4 of Fig. 3; Fig. 5 is a vertical longitudinal section on the line 5—5 of Fig. 3; Fig. 50 6 is a vertical longitudinal section on the line 6—6 of Fig. 3; Fig. 7 is a vertical longitudinal section on the line 7—7 of Fig. 3; Fig. 8 is a section on a larger scale, taken on a vertical longitudinal plane at the receiving 55 end of one of the chains to illustrate the manner in which the chains and dogs are

guided to cause the gill-pins to penetrate the fiber with a substantially direct upward movement; and Fig. 9 is an enlarged perspective view of one of the dogs. 60

The drawings illustrate an apparatus comprising two chains, the chain designated 1 being driven at a relatively lower speed and delivering the fiber to the chain 2, which operates at a relatively higher speed. For 65 convenience the chains will be referred to as the low speed and high speed chains, respectively, it being understood that these terms are used relatively. The driving connections whereby the difference in speed is 70 secured are not illustrated, as this feature of operation is familiar to those skilled in the art. The framework may be made in sections, corresponding to the length of the chains, and joined at their proximate ends, 75 as indicated at 3. The frame section including the low speed chain 1 comprises two side plates 4 and 5, united by suitable cross-members, represented by the beam 6. Similarly, the frame of the high speed chain 2 comprises side members 4^a and 5^a and cross-members including the beam 6^a. 80

The chain 1 comprises a series of parallel gill-bars 7 bearing the usual gill-pins 8 and mounted rotatably at their end portions in 85 two parallel series of links 9, the chain being preferably of that type of construction in which the gill-bars are independent of the joints of the links, so that the bars are not subjected to the pulling strains, which are 90 transmitted only from link to link. The construction indicated in Fig. 3 is that disclosed in my Patent 1,048,526 of December 31, 1912, 95 wherein every alternate link is provided with a boss 10 inserted within the eye of the adjacent link, which thus forms a link joint, and the gill-bar is mounted or journaled inside of the boss, which is tubular for the purpose.

Means for guiding the work or upper 100 stretch of the chain 1 comprise spaced parallel lower and upper rails 11 and 12, of which the rails 11 rest on cross-beams 6, while the upper rails 12 are supported from overhanging brackets 13, the chain guides 105 thus formed being spaced inward of the side frames. This portion of the chain guide-way (by which term I intend to include the similar guiding provisions at both sides of the machine) is traversed by the links, as 110 clearly shown in Fig. 3. At the delivery end of the circuit, however, where the chain

rounds the curves or bends, the guiding control upon the chain is transferred from the links to the gill-bars themselves at portions of the latter inside of the links. To this end vertical plates 14 are disposed inward of the end portions of the rails 11, being supported from the side frames by brackets 15, which are set backward sufficiently from the end of the circuit to permit the free passage of the dogs between the plates and the side frames. The outer edge of each of the said plates is fashioned with a guide flange 16, which is advantageously of substantial width and comprises, as shown in Fig. 5, an approximately straight top portion overlapping the terminal portion of the rail 11 and leading to a curved portion at the delivery bend, which curved portion merges into a straight downwardly inclined portion leading in turn to a curved portion at the return bend. The extremities of the guide flange may be additionally incurved, as shown, for the purpose of insuring easy entrance of the guided parts in either forward or backward driving of the chain. The terminal portions of the rails 11 and 12, which extend substantially to the delivery bend, are curved for a similar purpose, as shown in Fig. 6. In the vicinity of the return bend the plates 14 are supplemented in their duty of guiding the gill-bars by guide flanges 17, disposed vertically below the flanges 16 and carried by plates 18, having bracket portions 19 supporting them in inwardly spaced relation from the side frames. These guides conduct the chain for a suitable distance beyond the return bend, from which point onward the return stretch of the chain may be guided or unguided as preferred. The construction at the opposite end of the low speed chain 1 is not illustrated, since it may be like the receiving end of the high speed chain 2 or of other character without affecting the invention. The chain is further guided at the delivery and return ends by upper and lower pairs of carrying wheels 20 and 21. The shafts 22 and 23 of these wheels are journaled in bearings 24 and 25 in the plates 14, and are consequently spaced at their ends from the side frame so as to permit the passage of the arms of the dogs 30, which may be made of considerable length. The wheels may have either plain or notched peripheries, both being known in the art, but are preferably plain and are of different diameters, the upper wheels being substantially smaller than the lower because of the desirability of securing a sharp bend in the chain at the point where the gill-pins fall out of the fiber. The driving of the chain may be effected by wheels 26 having teeth engaging the gill-bars inside of the chains, these wheels being mounted on a cross-shaft 27, which in Fig. 1 is indicated as being driven

from a longitudinal shaft 28 through gearing 29.

The dogs 30 are fixed on the ends of the gill-bars outside of the links, their purpose being, as is well understood, to coöperate with suitable grooves or trackways to control the rake of the gill-pins, more especially throughout the working stretch and while rounding the ends of the circuit. Each dog comprises a hub 31, which receives the end of the bar, and two arms 32 and 33, which may be termed the main and auxiliary arms and which coöperate at different times with main and auxiliary trackways presently to be described. In my prior Patent, No. 1,048,526, mentioned above, there is disclosed a dog having arms disposed, as here, in substantially right-angular relation to each other, and extending obliquely to the axis of the gill-bar. In that construction, however, the inclination of both arms was laterally outward, whereas in accordance with the present invention the arms have reverse inclinations, the arm 32 being inclined laterally outward and the arm 33 laterally inward, from which construction and relation important benefits accrue, as will presently appear. The extremities of the dog arms are provided with cylindrical bosses 34 and 35, which in the present invention project in opposite directions, the bosses of the outwardly inclined main arms being directed outward and those of the inwardly inclined auxiliary arms extending inward, with respect to the side lines of the chain.

The main trackway, in which the bosses 34 are guided, comprises plates 36 applied to the inner faces of the side frames and formed with guide grooves 37 extending in or adjacent the horizontal plane of the working stretch of the chain guideway, so that during the forward travel the main arms 32 trail more or less directly behind their gill-bars, the auxiliary arms 33 and the pins 8 being substantially vertical or maintained with a slight rake, which is preferably rearward in the latter part of the stretch. These main dog guides terminate in downwardly curved extremities adjacent the return bend, where the control of the dogs is assumed by the auxiliary trackway, comprising grooved plates 38 supported at substantial distances inwardly of the side frames, as by means of studs 39 above and bracket portions 40 below. The main and auxiliary trackways are thus disposed in laterally spaced planes, and their grooves, it will be noted, face in opposite directions, to correspond with the outwardly and inwardly directed bosses 34 and 35 of the main and auxiliary arms, respectively. The auxiliary trackways are suitably formed to conduct the dogs around the delivery and return bends and through the downwardly extending stretch connecting the same, in such manner as to cause the pins 139

to pass downward out of the fiber substantially vertically, and thereafter to prevent interference between the dog arms, as indicated in Fig. 4. The upper portions of the auxiliary trackway guides overlap the main trackway guides of the working stretch, and their lower portions extend rearward for a suitable distance in the direction of the return stretch. After the bosses 35 of the auxiliary arms of the dogs leave these lower portions of the auxiliary trackway guides, the dogs may be unguided while traveling through the return stretch, or guides similar to the guides 41^a of the high speed chain 2, presently to be described, may be present to receive the bosses 34 of the main arms to conduct the dogs through the return stretch to such receiving and guiding means as may be provided at the remote end of the circuit.

The high speed chain 2 is in all substantial respects like the first chain, from which it receives the hemp, and comprises the bars 7^a with pins 8^a and the links 9^a, in which the ends of the bars are pivotally mounted. The dogs 30^a of this chain resemble the dogs of the first chain, having main and auxiliary arms 32^a and 33^a with bosses 34^a and 35^a, respectively. The relations may differ, however, to the extent that the pins 8^a are inclined slightly forward with respect to the auxiliary arms 33^a. The chain guide rails 11^a and 12^a correspond to the parts 11 and 12 heretofore described and are indicated as being similarly supported. The main trackway guides, for controlling the dogs during their travel through the working stretch, are designated 36^a, and 41^a are trackway members which guide the main dog arms through the return stretch to the receiving end of the circuit. The chain is guided to the receiving end of the circuit on the flanges 17^a of guide members 18^a, similar in general respects to the parts 17 and 18 adjacent the return bend of the low speed chain. At the receiving end of the circuit of the high speed chain, however, the gill-bars are carried and guided by a single pair of wheels 43 mounted on a cross-shaft 45, the ends of which are mounted in side frames 4^a and 5, since at the receiving end of the circuit, owing to the disposition of the dogs, it is not necessary to provide for clearance of the shaft by the arms as is the case at the delivery end. The auxiliary trackway guides 38^a are mounted in a manner similar to the auxiliary trackway guides 38 of the low speed chain, and guide the auxiliary arms 33^a during the travel of their gill-bars around the wheels 43. It will be observed that, owing to the reverse lateral inclinations of the two arms of each dog in both of the chains, it is possible for the inwardly inclined arms 33 of the low speed chain to pass in overlapping relation to the outwardly inclined arms 32^a of the high speed chain, thus enabling the proximate

ends of the chain to be brought very close together, with the consequent advantage of a short nip upon the fiber. The main arms 32 of the low speed chain are inclined outward rather than inward, in order to secure the benefits of long arm action, these arms being, as indicated, substantially longer than the spaces between the gill-bars, and because of their outward inclination being free to overlap each other to as great an extent as may be desirable. The same advantage flows from the outward inclination of the arms 33^a of the high speed chain, and in addition these arms are enabled to pass the inward inclined auxiliary arms 33 of the low speed chain, as just described. While the auxiliary arms 33^a of the high speed chain might be inclined outward, as in my prior Patent, 1,048,526, above referred to, as far as the function of insuring a short nip is concerned, it is advantageous to have them extended obliquely inward like the auxiliary arms 33 of the low speed chain, because this relation enables the auxiliary trackway 38^a to overlap the main trackways 36^a and 41^a in the crossing relation shown in Fig. 4, this being possible because the main and auxiliary trackways are laterally spaced with respect to each other. The crossing relation of the trackways at the receiving end of the high speed chain is important to the proper control of the dogs, and thereby of the bars and gill-pins. Manifestly the same relation may obtain in the low speed chain.

The organization of the chain and dog-guiding means at the receiving end of the high speed chain is such as to secure substantially direct penetration of the fiber by the pins in the manner represented in Fig. 8. It will be observed that the trackway guides 38^a for the auxiliary arms of the dogs are formed with curved portions 46, which may be approximately concentric with the axis of the wheels 43 and disposed at such distance from their peripheries that the gill-pins as they rise and approach the hemp line assume a forward inclination, which inclination they possess when their extremities enter the fiber. At this point the bosses 35^a encounter portions 47 of the trackway groove which are substantially vertical or inclined slightly forward and which compel the upper portions of the pins to rise substantially straight upward through the fiber, while their hubs attached to the gill-bars are being carried upward and forward around the wheels, the pins thus straightening as they rise. The portions 47 of the trackway grooves are of such length that when the successive bosses 35^a reach the upper ends of the said portions, the corresponding pins have assumed the substantially erect position shown at the left of Fig. 8. From this point onward for a short distance the bosses 35^a of the auxiliary dog arms travel through

forwardly extending portions 48 of the auxiliary trackway grooves, the bosses 34^a of the main arms at the same time entering the inlet ends of the main trackway guides 36^a.

While I have described the preferred embodiment of my invention in detail, it is to be understood that I do not limit myself to the precise construction shown, and that numerous changes may be made without departing from essentials. Furthermore, while the invention is primarily an improvement in hackle chain apparatus, the dog herein described need not as a matter of use be limited to such mechanism solely and certain of the appended claims are designed to cover the same and its relations for other kinds of chain devices.

What is claimed as new is;

1. In hackle-chain apparatus, the combination with a series of gill-bars rotatably mounted in parallel series of links, and main and auxiliary dog-trackways, of dogs on the ends of the gill-bars, each dog comprising main and auxiliary arms coöperative with said trackways; the said arms being disposed at an angle to each other and having reverse lateral inclinations.

2. In hackle-chain apparatus, the combination with a frame provided with chain-guiding means and main and auxiliary dog trackways, of a chain comprising parallel gill-bars rotatably mounted in and joining two parallel series of connected links, the joints whereof are independent of the gill-bars, and dogs on the ends of the gill-bars, each dog comprising main and auxiliary arms disposed at approximately a right angle to each other and extending obliquely to the axis of the gill-bar, the two arms being reversely inclined.

3. In hackle-chain apparatus, the combination of a chain of gill-bars rotatably mounted in two parallel series of links, dogs on the ends of said gill-bars having each two arms at an angle to each other and inclining respectively outward and inward with respect to the lateral plane of the chain, and trackways in laterally offset planes for guiding said arms.

4. In hackle-chain apparatus, a gill-bar dog coöperative with trackways to control the rake of the hackle-pins, said dog comprising arms having reverse lateral inclinations.

5. A dog for hackle-pin and other chain apparatus comprising a hub, and arms projecting therefrom in angular relation to each other and at reverse lateral inclinations, having oppositely projecting bosses at their extremities.

6. In hackle-chain apparatus, the combination with a hackle-chain comprising a series of gill-bars and two series of links in which the gill-bars are rotatably mounted, and means for guiding the chain, of dogs on

the ends of the gill-bars, each dog having main and auxiliary arms disposed at an angle to each other and at reverse lateral inclinations and provided at their extremities with oppositely projecting bosses, a main trackway controlling the bosses of the main arms through the working stretch, and an auxiliary trackway for controlling the bosses of the auxiliary arms at the end of the circuit.

7. In hackle-chain apparatus, the combination with a chain of gill-bars rotatably mounted in two parallel series of links, of dogs on the ends of the gill-bars having each two arms provided with oppositely projecting lateral bosses, and trackways in laterally spaced planes for the reception of said bosses.

8. In a hackle-chain apparatus, the combination with a chain of gill-bars and means for guiding the same, of dogs on the ends of the gill-bars each provided with laterally offset guiding portions, and trackways in laterally spaced planes and in crossing overlapping relation for receiving said guiding portions.

9. The combination of a chain comprising rotatably mounted members, dogs carried by said members for controlling the same, said dogs each comprising two arms at an angle to each other and having reverse lateral inclinations, and trackways coöperative with said arms at different parts of the circuit.

10. Hackle-chain apparatus, comprising two chains of gill-bars, one delivering to the other and each provided on the ends of its gill-bars with dogs, the dogs of both chains having each two arms oblique to the axis of its gill-bar and in reverse inclination to each other, the dogs at each side of each chain thereby constituting two obliquely offset sets of arms of which the outwardly inclined set of one chain overlaps the inwardly inclined set of the other chain at the proximate ends of the circuits.

11. Hackle-chain apparatus, comprising two chains of gill-bars one delivering to the other, guideways for the chains, dogs having arms oblique to the axes of the gill-bars, and trackways for said arms, said dogs comprising a set of outwardly inclined arms in one chain passing in overlapping relation a set of inwardly inclined arms in the other chain at the proximate ends of the circuits.

12. In hackle-chain apparatus, a chain of gill-bars having dogs thereon, and a trackway controlling the dogs at the receiving end of the circuit, the parts being so constructed and organized that the gill-pins approach the hemp line at a forward inclination straightening as they rise.

13. Hackle-chain apparatus, comprising two chains of gill-bars one delivering to the other, and means controlling the gill-bars of the second chain at the receiving end of their

circuit whereby the gill-pins approach the hemp line at a forward inclination straightening as they rise.

14. In hackle-chain apparatus, the combination with a chain of gill-bars having dogs, means at the receiving end of the circuit for guiding the gill-bars through a curved path into the working stretch, and a trackway arranged to guide the dogs of the gill-bars traveling in the upper portion of said curved path, said trackway comprising a curved portion leading to an approximately straight upwardly extending portion causing the gill-pins to penetrate the fiber with an approximately direct upward movement.

15. In hackle-chain apparatus, a chain of gill-bars bearing dogs, and carrier wheels for conducting the gill-bars from the return stretch upwardly in a curved path to the working stretch, in combination with a dog trackway having a portion approximately concentric with the carrier wheels leading to an approximately upright portion, which latter is so positioned as to control the dogs during the penetration of the fiber by the gill-pins connected therewith.

16. In a hackle-chain apparatus, the combination with a chain comprising gill-bars and links, dogs on the ends of the gill-bars, and trackways for the dogs, of a chain guideway comprising a portion for guiding the working stretch of the chain, said portion terminating near the delivery end of the circuit and being engaged by the links, and other stationary portion for guiding the chain at the delivery end, the latter portion being engaged by the gill-bars at points inside of the links.

17. In a hackle-chain apparatus, the combination with a chain comprising gill-bars and links, dogs on the ends of the gill-bars, and trackways for the dogs, of means for guiding the chain comprising guides for the working stretch disposed so as to be engaged by the links, carrier-wheels for carrying the gill-bars around the bends at the delivery end of the circuit, and stationary guides adjacent the said carrier wheels also engaged by the gill-bars.

18. In a hackle-chain apparatus, the combination with a chain comprising gill-bars and links, dogs on the ends of the gill-bars, and trackways for the dogs, of carrier-wheels for carrying the chain around the delivery bend, and a chain guideway comprising guides for the working stretch and delivery terminal of the circuit, said guides overlapping each other adjacent the said wheels and being engaged by the links and by the gill-bars, respectively.

19. In a hackle-chain apparatus, the combination with a chain comprising gill-bars and links, dogs on the ends of the gill-bars,

and trackways for the dogs, of stationary chain-guiding means comprising guides for the working stretch engaged by the links and separate guides engaged by the portions of the gill-bars inside of the links for conducting the chain to and through a downward-extending terminal stretch leading to a return stretch.

20. In a hackle-chain apparatus, the combination with a chain comprising gill-bars and links, dogs on the ends of the gill-bars, and trackways for the dogs, of stationary chain-guiding means comprising guides for the working stretch engaged by the links and guides overlapping and disposed inwardly of the working stretch guides for engagement by the gill-bars, the latter guides comprising delivery and return bend portions connected by a straight downwardly-extending portion.

21. A hackle-chain apparatus, comprising side frames, a chain running therebetween and comprising gill-bars connected with two parallel series of links and provided at their ends with dogs, trackways for controlling said dogs, and upper and lower longitudinal guide rails supported inwardly of the side frames and receiving the links between them to guide the chain through its working stretch, in combination with a guide structure at the delivery end of the working stretch supported inwardly of the guide rails in order to be engaged by the gill-bars, carrying wheels at the said delivery end, and a shaft for the carrying wheels mounted in said guide structure.

22. A hackle-chain apparatus, comprising side frames, a chain running therebetween and comprising gill-bars connected with two parallel series of links and provided at their ends with dogs, trackways for controlling said dogs, and upper and lower longitudinal guide rails supported inwardly of the side frames and receiving the links between them to guide the chain through its working stretch, in combination with a guide structure comprising plates supported by brackets inwardly of the guide rails at the delivery end of the working stretch and having guide surfaces engaged by the gill-bars, said guide surfaces comprising curved portions at the delivery and return bends and intermediate downwardly-extending portions, and upper and lower carrying wheels disposed adjacent said curved portions and having their shafts supported in said guide structure.

In testimony whereof, I have signed this specification in the presence of two witnesses.

JOHN GOOD.
